HENRY GREY, OF NEW YORK, N. Y., ASSIGNOR TO AMERICAN UNIVERSAL MILL COMPANY, OF NEW YORK, N. Y., A CORPORATION OF WEST VIRGINIA.

INGOT-MOLD.

No. 818,684.

Specification of Letters Patent.

Patented April 24, 1906.

Application filed October 3, 1902. Serial No. 125,848.

To all whom it may concern:

Be it known that I, HENRY GREY, a citizen of the United States of America, residing at New York, in the county of New York and State of New York, have invented certain new and useful Improvements in Ingots-Molds; and I hereby declare the following to be a full, clear, and exact description of the invention, such as will enable others skilled in the art to which it pertains to make and use the same.

My invention relates to improvements in molds for use in casting metal ingots, especially steel ingots, and has reference more especially to metal molds suitable for casting ingots for the manufacture of I-beams or flanged bars or girders or structural work of any profile or cross-section other than square, round, or rectangular, reference being made 20 to the accompanying drawings, hereinafter more particularly referred to.

In the said drawings, Figure I is a side elevation of an ingot-mold embodying my invention. Fig. II is a top plan of the said mold. Fig. III is a right-hand side elevation relative to Fig. I, partly in section on lines III III, Fig. I. Fig. IV is an elevation corresponding with Fig. III except as to the illustration of certain features or peculiarities herein-30 after referred to.

The most advantageous shape for a cast-steel ingot is one nearly as possible approximating the shape and proportion of the finished bar or product to which the ingot is to be reduced without unduly increasing the cost of the ingot-mold or decreasing the necessary amount of work which any rolled-steel product should have, so as to obtain its maximum amount of ultimate tensile strength, 40 elastic limit, and elongation. When an ingot is made for an I-beam and the cross-sectional area and thickness of the web of the ingot bear to the cross-sectional area and thickness, respectively, of the web of the finished beam the same or approximately same ratio which the cross-sectional area and mean thickness of the flanges or heads of the ingot bear to the cross-sectional area and mean thickness, respectively, of the heads or flanges of the finished beam, the whole ingot, web, and flanges can be rolled or elongated proportionately and without undue strains being set up or occurring by reason of one part of the section or blank being unduly elongated and having to

drag the other part of the blank or section along with it, thus producing uneven ends and increasing the amount of steel that goes into scrap instead of finished product or material. Also if the shape of the ingot approximates the shape of the finished beam or product much unnecessary work, especially for making a large-sized product, is dispensed with. It is well known that molten steel contracts in cooling, and it is also well known that cast-iron expands upon becoming heated, hence the difficulty of making a steel ingot in a cast-iron mold when the ingot is of greater thickness at one or both sides or ends than in its central portion or web. The mold when the molten steel is poured into it obviously expands and that part of the mold contiguous to the web of the ingot elongates from expansion and presses against the inner surfaces of the steel which forms the flanges of the ingot. As the mold becomes gradually hotter and expands in proportion and the molten steel contracts as it becomes cooler and solidifies, it follows that in a solid and non-parable mold, the two opposing forces working in opposite directions and the molten steel in a greater proportion than the iron of the mold, the ingot would bind itself with irresistible force upon that part of the mold contiguous to the inner sides of the flanges of the ingot and would crack the ingot while cooling at the junction of the said sides of the flanges of the ingot with the web of the ingot—that is, at the points marked 17 in Fig. II. It is evident therefore that unless means are adopted to obviate this difficulty in making an ingot which in cross-section is thinner in its central portion or web than at the heads or flanges it will either be very difficult to strip the mold from the ingot, or to obtain an ingot which when stripped is free from the imperfections hereinbefore mentioned.

I would here remark that an ingot of the character indicated should not only be cast in a parable mold, but the ingot should be made of such shape—that is, the slope of the inner sides of the flanges of the ingot inwardly toward the web or body portion of the ingot should be long enough—that while the cross-sectional area and mean thickness of the flanges of the ingot bear to the cross-sectional area and mean thickness, respectively, of the flanges of the finished beam of the same or approximately same ratio which

the cross-sectional area and thickness of the web or body portion of the ingot bear to the cross-sectional area and thickness, respectively, of the web or body portion of the finished beam or product the ingot shall participate in the release of the mold from the ingot and free itself from strains likely to disrupt it. Obviously as the hot molten steel is poured into the mold the inner surfaces of the mold become heated before the exterior of the mold, and there will be a tendency to elongate the said inner surfaces before the said exterior, thus making the mold, if it were of the partible type, as is the case in this invention, assume, if allowed, a shape approximately that shown in exaggerated form in Fig. IV and marked by dotted lines 14, which diagrammatically represent the upper and lower ends of the separable upper halves or sections 1 and 2 of the mold as sloping somewhat outwardly. After the heat has become uniform throughout—that is to say, when the heat of the outside of the mold has become approximately equal to that of the interior of the mold—the mold returns to a perpendicular outline.

It is the purpose of my invention to allow the mold to expand to a limited extent in the way most easy to itself and to provide means for preventing the upright halves or sections of the mold after expanding and becoming separated from returning to their original and normal positions relative to each other. The said mold-sections before casting should be as close together as possible, as is shown in Figs. I and III, at the points marked 20, while after casting there should be between the said sections a space equal to the mean expansion of the mold, which space is represented in Fig. IV as being between the two dotted lines 12 and between the two unbroken lines 22.

The object of my invention is to provide a partible mold for casting an ingot having the desired shape and proportion relative to the contour of the beam or product to which the said ingot is to be reduced, to render the mold readily removable from the ingot by such machinery as is in use in all modern rolling-mills without leaving the ingot in a disrupted or partially disrupted or imperfect condition, and generally to successfully avoid the difficulties or objectionable features heretofore encountered in the use of partible ingot-molds.

With this object in view and to the end of realizing other advantages hereinafter appearing this invention consists in certain features of construction and combinations of parts hereinafter described, and pointed out in the claims.

My improved longitudinally-partible ingot-mold comprises two vertically-arranged or upright sections 1 and 2, which have the contour and arrangement required to form

opposite halves or portions, respectively, of the interior chamber of the mold at opposite sides, respectively, of the joints 20 between the said sections. The said chamber is enlarged laterally, as at 18, adjacent to each joint 20 in opposite directions, and consequently into each of the said mold-sections, so as to render the mold suitable for casting an ingot having a web or body portion between two heads or flanges. The inner side wall 16 of each lateral enlargement 18 of the chamber of the mold slopes inwardly considerably or appreciably toward the contiguous side wall 21 of the central portion of the said chamber, as shown very clearly in Fig. II. Each sloping wall 16 is arranged preferably at an obtuse angle of about one hundred and thirty-five degrees to the contiguous wall 21.

The mold-sections 1 and 2 are assembled and rest removably upon a stool or base 11.

Adjacent to each joint 20 between the mold-sections 1 and 2 and externally of the mold are two tie rods or bolts 5 and 5, which are arranged horizontally and cross the said joint externally of the upper portion and lower portion, respectively, of the mold. Each bolt 5 extends through two correspondingly arranged and registering ears 4 and 4, which are formed upon and integral with the different mold-sections 1 and 2, respectively. Each bolt 5 extends a suitable distance outside of and beyond the outer ends of the engaging ears and is provided with screw-threads upon its end portions beyond the said ends of the said ears. Each threaded end of each bolt 5 bears a correspondingly-threaded nut 6, which engages with threads upon the bolt, and next to the inner end of the said nut is a washer 8. One of the nuts 6 upon each bolt 5 is arranged far enough from the outer end of the adjacent bolt-engaged ear to accommodate the location between the said ear and the washer next adjacent to the inner end of the said nut of a spiral spring 9, which is coiled upon the bolt and confined between the said ear and the said washer. Each bolt 5 is enlarged diametrically between the ears 6, through which the said bolt extends. The said central and diametrically-larger portion of the said bolt extends into the inner end of the ear, which forms an abutment for the spring on the said bolt, which ear has the bolt-receiving hole thereof larger diametrically in the inner end of the ear to freely accommodate the location of the said central and diametrically-larger portion of the bolt. The central and diametrically-larger portion of each bolt 5 is provided with a slot 13, which extends vertically through as well as longitudinally of the bolt and in the normal or closed-together position of the mold-sections 1 and 2 is partially covered by the surrounding wall of the inner enlarged end of the bolt-receiving hole of the ear, which is engaged by

the spring upon the said bolt, and a correspondingly vertically arranged downwardly-tapering key or wedge 10 engages the said slot and is contiguous to the inner end of the 5 said ear. The relative arrangement of the parts is such that when the mold-sections 1 and 2 are in their normal position and close together, as shown in Figs. I, II, and III, the key or wedge 10 of each bolt 5 is in its elevated 10 position, but when the mold expands, so as to result in a separation of the mold-sections 1 and 2 at the joints 20, the two ears 4, engaging the said bolt, will become farther separated, and consequently the said key or 15 wedge will gradually descend while the mold is gradually expanding, and thereby hold the said mold-sections apart.

Fig. IV, as already indicated, illustrates the approximate condition of the mold and 20 attachments after the mold has become approximately uniformly heated throughout and shows the two mold-sections 1 and 2 apart to the extent of the space between the lines 12 and 12 and between the lines 22 and 25 22 and the keys or wedges 10 dropped down and forming means for preventing the said mold-sections from returning toward each other to their former and normal position. (Shown in Figs. I, II, and III.) Fig. IV also 30 shows the springs 9 partially compressed, but with sufficient leeway left to allow of the mold-sections 1 and 2 separating still farther when the stripping-machine (not shown) is brought into operation to draw the ingot 35 mold from the ingot.

By the construction hereinbefore described it will be observed that the nuts 6 upon each bolt or rod 5 form stops, which are instrumental in limiting endwise movement of the 40 said rod or bolt in opposite directions, respectively, and that the spring upon the said bolt being confined between one of the said stop-forming members and the adjacent ear 4 constitutes an elastic and compressible device, which acts to retain the mold-sections 1 and 2 in their normal position and has a range of compression not only sufficient to 45 accommodate an expansion and separation of the mold-sections from heat, but adequate 50 to permit a farther separation of the mold-sections, if required, during the withdrawal subsequently of the mold from the ingot.

The mold-sections 1 and 2 are provided externally and at and contiguous to the top and 55 outer end of each ear 4 with a shield-forming flange 15, which overhangs the nut-bearing portion of the bolt which extends through the said ear and also overhangs the spring of the said bolt, if the bolt is provided with a 60 spring, so that the nuts 6, the springs 9, and the threaded ends of the bolts 5 are amply protected and not liable to be injured or interfered with by accidentally-spilled molten metal.

65 As already indicated, in the preferred form

of ingot suitable for making a bar or beam having a web between two flanges the cross-sectional area and mean thickness of the flanges of the ingot bear to the cross-sectional area and mean thickness, respectively, of the 70 flanges of the finished beam or bar to which the ingot is to be reduced the same or approximately same ratio which the cross-sectional area and thickness of the web of the ingot bear to the cross-sectional area and thickness, respectively, of the web of the said final product, and consequently the interior chamber of my improved mold has such outline in horizontal cross-section relative to the cross-sectional outline of the finished product 75 to which the ingot cast in the mold is to be subsequently reduced that the distance between opposite internal side walls of the mold's portion in which the web of the ingot is formed bears to the mean distance between opposite side walls of the lateral enlargements of the chamber the same or approximately same ratio which the thickness of the web of the aforesaid final product bears to the mean thickness of the flanges of 80 the said product.

The parts of the mold are assembled and operate as follows: The bolts are placed in position and then the mold-sections 1 and 2 assembled upon the base 11. The nuts 6 95 upon each bolt 5 are tightened enough to make the joints between the said mold-sections sufficiently tight; but the springs 9 have sufficient leeway to freely permit an expansion of the mold. The tapered keys or 100 wedges 10 are then placed in the slots in the bolts. It will be observed that the ear-engaging edge of each wedge or key 10 is straight vertically, that the opposite edge of the said key or wedge slopes downwardly and 105 inwardly, and that the wall of the slot which is engaged by said sloping edge of the wedge or key slopes correspondingly. The slot in each bolt 5 is long enough to provide room when the mold expands and presses or acts 110 against the action of the spring upon the said bolt for the engaging wedge or key to drop farther in the said slot, and thereby prevent the mold-sections 1 and 2 from returning to each other. In casting the ingot when the 115 parts have been assembled, as shown in Figs. I, II, and III, the molten metal is then poured into the mold. Obviously the part of the mold—the inside—with which the molten steel makes contact expands, while the outside of the mold, where the heat has not yet arrived, refuses to expand. The effort of the 120 inside of the mold to lengthen out bends the mold-sections 1 and 2 into the arcs of large circles, as shown approximately and diagrammatically by the dotted lines 14 in Fig. IV. This action causes a farther separation of the 125 two ears 4, engaged by each tie-bolt 5, and results in a compression of the spring 9 of the said bolt and enables the wedge or key of the 130

4
 said bolt to fall farther into the slot 13 of the bolt. Now when the mold has become heated throughout it will readily be understood that the outside of the mold also lengthens out, but as the keys or wedges 10 prevent the end portions of the mold-sections 1 and 2 from returning to their original or normal position the middle or central portions of the said mold-sections draw back or away from each other, so as to leave the said mold-sections held separated to the extent of the space between the two dotted lines 12 or between the two unbroken lines 22 in Fig. IV. The outside of the ingot is chilled by its contact with the cool iron mold and is thoroughly capable of holding itself in shape by the time the mold has expanded and the mold-sections 1 and 2 are in the position indicated by the lines 12 and 22. The mold thus having automatically enlarged the space within it and the ingot by reason of its greater or less degree of solidification having decreased the space necessary for itself, it follows that if the slope of the walls 16 is long enough the mold can be readily withdrawn from the ingot, but if there should still be some tendency for the inner sides of the heads or flanges of the ingot to bind upon or attach to the walls 16 of the mold then when by the application and operation of the machine, (not shown,) which is called a "stripper," the ingot is held still while pressure is exerted upwardly against the lower ends of the lugs 19, with which the upper portions of the mold-sections 1 and 2 are provided externally the capability of the springs 9 to be compressed still farther will coöperate with the appreciable inwardly-sloping walls 16 of the mold to accommodate and facilitate a farther separation of the mold-sections when the ingot is held still, as aforesaid, during the operation of the stripper to withdraw the mold from the ingot.

I would here remark that especially important is the arrangement of the inner side wall 16 of each lateral enlargement 18 of the chamber of the mold at an obtuse angle of considerable degree to the contiguous side wall 21 of the said chamber in connection with the capability of the springs 9 to be further compressed after the compression of the said springs by the expansion and separation of the mold-sections from heat and the operation of the keys 10, so that any imperfections upon or in the opposing surfaces of a wall 16 of the mold and the adjacent head or flange of the ingot cast in the mold—such, for instance, as a swell or projection on one of the said surfaces engaging a recess in the other of the said surfaces—will instead of locking or attaching or binding the ingot to the mold participate during the withdrawal of the mold from the ingot in a farther separation of the mold-sections against the action of the aforesaid springs; but such ad-

ditional separation of the mold-sections obviously could not take place if the walls 16 were not arranged at an appreciable obtuse angle to the contiguous walls 21 and the aforesaid springs had not the capability to yield still farther after their partial compression by the expansion of the mold-sections from heat. In other words, in order to prevent locking of the mold-sections to the ingot at the inner sides of the heads or flanges of the ingot by imperfections present in or on the opposing surfaces of the ingot and mold at the said inner sides of the flanges or heads of the ingot the springs or means acting to yieldingly hold the mold-sections in their normal position and close together have not only the capability of affording a separation of the mold-sections to accommodate the expansion of the said mold-sections from heat, but are yieldable still farther to accommodate a farther separation of the said mold-sections when the ingot is held still during the withdrawal of the mold from the ingot, and the angle of inclination of the inner side walls 16 of the enlargements 18 of the chamber of the mold is considerable, or at least sufficient, to accommodate and facilitate such farther separation of the mold-sections. I would remark also that the ingot-flanges formed in the enlarged portions 18 of the chamber of the mold during the casting of the ingot will during the contraction of the ingot in the mold after an expansion or separation of the mold-sections from heat during the operation of the mold operate as wedges which act outwardly against the sloping walls 16 of the said enlargements, and thereby operate to separate the separable mold-sections still farther.

What I claim is—

1. A portable ingot-mold comprising a pair of upright sections having the arrangement and contour required to form opposite halves or portions, respectively, of the chamber of the mold, which mold-sections have a limited movement apart and are normally arranged close together; means externally of the mold, at each joint between the said mold-sections, for tying the said sections together, which means comprises a tie rod or bolt extending across the said joint, which bolt or rod has a slot arranged between and a suitable distance from the ends of the rod or bolt; two ears embracing the said bolt and formed upon the different mold-sections respectively, and one of the said ears partially covering the aforesaid slot; stop-forming members on the said bolt or rod at the outer ends of the said ears and instrumental in limiting endwise movement of the rod or bolt in opposite directions respectively; an elastic device upon the bolt or rod and confined between one of the said stop-forming members and the adjacent ear and acting to retain the aforesaid mold-sections in their

- normal position, and a tapering key or wedge engaging the aforesaid slot. 50
2. A portable ingot-mold comprising upright sections having the arrangement and contour required to form the chamber of the mold, which mold-sections have a limited movement apart and are normally arranged close together; means externally of the upper portion as well as externally of the lower portion 55 of the mold, at each joint between the said mold-sections, for tying the said sections together, which means comprises a tie bolt or rod arranged in a horizontal plane and having a slot; two ears embracing the said bolt or rod at opposite sides respectively of the adjacent joint between the aforesaid mold-sections and projecting from the different mold-sections respectively, and one of the said ears normally covering a portion of the aforesaid slot; stop-forming members on the rod or bolt at the outer ends of the said ears and instrumental in limiting endwise movement of the bolt or rod in opposite directions respectively; a spiral spring on the bolt or rod 60 and confined between one of the stop-forming members and adjacent ear and acting to retain the aforesaid mold-sections in their normal position, and a tapering key or wedge engaging the aforesaid slot. 65
3. A portable ingot-mold comprising upright sections forming the chamber of the mold, which sections have a limited movement apart and are normally arranged close together; means externally of the mold at each joint between the said mold-sections for tying the said sections together, which means comprises a tie bolt or rod arranged in a horizontal plane, which rod or bolt has a slot which is arranged between and a suitable distance from the ends of the bolt or rod; two ears embracing the said rod or bolt and formed upon the different mold-sections respectively, and one of the said ears normally covering a portion of the aforesaid slot; stop-forming members on the rod or bolt at the outer ends of the said ears and instrumental in limiting endwise movement of the bolt or rod in opposite directions respectively; an elastic device on the rod or bolt and confined 70 between one of the said stop-forming members and the adjacent ear and acting to retain the aforesaid mold-sections in their normal positions; a tapering key or wedge engaging the aforesaid slot; and a shield-forming flange or member formed at the top and outer end of each ear and overhanging the adjacent portion of the bolt or rod and members upon the said rod or bolt at the outer end of the said ear. 75
4. A portable ingot-mold comprising sections forming the chamber of the mold, which sections have a limited movement apart and are normally arranged close together; means externally of the mold at the joints between the said mold-sections for tying the said sections together, which means comprises tie bolts or rods arranged in a horizontal or approximately horizontal plane and having a diametrically-enlarged central portion which has a slot extending from the upper side of the said portion downwardly; two ears embracing each rod or bolt and formed upon the different mold-sections respectively, and one of the said ears normally covering the aforesaid slot; stop-forming members on each bolt 80 or rod at the outer ends of the ears which embrace the said rod or bolt, which stop-forming members are instrumental in limiting endwise movement of the bolt or rod, and elastic means confined between one of the said stop-forming members and the adjacent ear and acting to retain the aforesaid mold-sections in their normal position, and the hole in one of the ears which embrace each rod or bolt being enlarged diametrically to receive the 85 diametrically-enlarged central and slotted portion of the said bolt or rod, and downwardly-tapering keys engaging the slots in the rods or bolts. 90

In testimony whereof I sign the foregoing specification, in the presence of two witnesses, this 6th day of September, 1902, at Cleveland, Ohio.

HENRY GREY.
